(57) **CLAIM**

We claim the ornamental design for a wipes dispenser with surface ornamentation, as shown and described.

DESCRIPTION

FIG. 1 is a top elevation view of a wipes dispenser with surface ornamentation showing our new design;

FIG. 2 is a bottom elevation view thereof;

FIG. 3 is a right side view thereof;

FIG. 4 is a left side view thereof; and,

FIG. 5 is a front elevation view thereof.

The surface shading represents contrasted color(s) but not a specific color.

The dot-dot-dash lines in the Figures are boundary lines which show an unclaimed boundary which forms no part of the claimed design.

The broken lines shown in the drawings represent portions of the wipes dispenser that form no part of the claimed design.
